WORK CLAMPING DEVICE

Leo I. Kaplan, Detroit, and Gustav von Reis, Grosse Pointe, Mich., assignors to Detroit Broach Company, Detroit, Mich., a corporation of Michigan

Application November 1, 1948, Serial No. 57,634

6 Claims. (Cl. 90—33)

1

This invention relates generally to work holding equipment, and refers more particularly to improvements in fixtures of the type employed to clamp work pieces in place while being processed.

One of the objects of this invention is to provide a relatively simple inexpensive fixture capable of being rapidly operated with ease and designed to hold a work piece firmly so that it will withstand cutting stresses of considerable proportions without working loose.

Another feature of this invention is to provide a work clamping fixture designed to securely hold the work during the cutting operation, so that the desired tolerances can be maintained and to accomplish this result without distorting the work.

Still another object of the invention is to provide a work clamping fixture having a swinging arm successively movable to work clamping and releasing positions in response to movement of a cam slide in either of two directions. This arrangement minimizes lost motion and enables the fixture to be used where high production is required.

A further feature of this invention is to provide a fixture of the above general type having a plurality of work clamping members successively movable as a unit to work clamping and work releasing positions in response to movement of the cam slide in each of the two directions of movement thereof.

The foregoing as well as other objects will be made more apparent as this description proceeds, especially when considered in connection with the accompanying drawings, wherein:

Figure 1 is a semi-diagrammatic front elevational view showing a work clamping fixture constructed in accordance with this invention and applied to a typical double slide broaching machine;

Figure 2 is a semi-diagrammatic side elevational view of the construction shown in Figure 1;

Figure 3 is a sectional view taken on the plane indicated by the line 3—3 of Figure 1;

Figure 4 is a sectional view taken on the plane indicated by the line 4—4 of Figure 3;

Figure 5 is a sectional view taken on the line 5—5 of Figure 3;

Figure 6 is a sectional view taken on the line 6—6 of Figure 2;

Figure 7 is a sectional view taken on the line 7—7 of Figure 3;

Figure 8 is a sectional view taken on the line 8—8 of Figure 3;

Figure 9 is a sectional view taken on the line 9—9 of Figure 1;

2

Figure 10 is a sectional view taken on the line 10—10 of Figure 9; and

Figure 11 is a semi-diagrammatic fragmentary perspective view of a part of the construction shown in Figure 1.

Although the work holding fixture forming the subject matter of this invention is not limited in its use to any specific type of machine, nevertheless, it finds particular utility when employed in connection with multiple slide type broaching machines. Accordingly, for the purpose of illustrating this invention, the work holding fixture is shown as installed on a typical double slide type broaching machine.

Such a machine is shown diagrammatically in the several figures of the drawings, and comprises generally a pair of laterally spaced vertical slides 12 and 13 respectively supporting suitable tools in the form of broaches 14 and 15. A table 16 is supported at the front side of the machine, and is suitably fashioned to respectively support a pair of horizontal slides 17 and 18.

Any suitable power mechanism, such for example, as hydraulic rams are provided for reciprocating the vertical slides, and the latter are operated in out-of-phase relationship, so that while one of the tools is moved downwardly on its cutting stroke, the other tool is retracted or moved upwardly to position the tool for the next cutting operation. In Figure 11 of the drawings, the tool or broach 14 is shown in a cutting position and the tool 15 is shown in a position on its retracting stroke. The horizontal slides may also be operated by suitable hydraulic rams arranged to move these slides in such timed relation to movement of the vertical slides that when one of the tools or broaches is on its cutting stroke, the adjacent horizontal slide is positioned in operative relation to this tool and the other horizontal slide is located in its rearwardmost or retracted position

with respect to the tool adjacent this slide. Referring again to Figure 11 of the drawings, it will be noted that the slide 17 is positioned in operative relation to the tool 14 and the slide 18 is located in its retracted position with respect to the tool 15. The specific means for operating the respective slides in the above timed relationship is not shown herein and may be any one of the accepted types employed on orthodox double slide broaching machines.

The specific contours of the tools or broaches 14 and 15 depend on the type of work to be processed. In the present instance the tool 14 has a cross sectional contour fashioned to machine a connecting rod bearing cap 19, and the tool 15 is contoured to sever the cap from a forged con-

necting rod indicated in Figure 9 by the reference character 28.

With the above in view, reference is now made more in detail to the work clamping fixture forming the subject matter of this invention. This fixture is shown in the several figures of the drawings as comprising a vertical slide 21, a pair of work clamping arms 22, 23 and a pair of work holding members 24, 15. In this connection it will be noted that the vertical slide 21 is actually formed integral with the tool slide 12 and extends for substantially the full length of the latter.

The arms 22 and 23 are respectively supported above the work molders 24 and 25 at the front side of the tools or broaches for swinging movement in laterally spaced substantially parallel vertical planes. In detail the work clamping arms are carried by a bridge or rigid support 26 which extends transversely of the tool slides at the front sides of the tools and is attached at opposite ends to the vertical frame of the machine by suitable brackets 27. The upper ends of the work clamping arms are respectively pivoted to the support 26 by a bar 29. As shown particularly in Figure 3 of the drawings, a pad 30 of wear resisting material is removably secured to the swinging or lower end of each arm by a stud 31. As will be more fully hereinafter set forth, the pads 30 are positioned on the swinging ends of the arms to engage the work to be clamped on the respective work holders.

In the present instance, the work holder 24 is fixed on the slide 17 and is formed with a recess 32 in the top face adjacent the inner side thereof. This recess is of sufficient dimension to receive a bearing cap 19, and as shown in Figure 8 of the drawings, is formed with shoulders 33 at opposite side edges for engaging the usual flanges on the cap 19 to locate the latter in a position where the cutting portion of the broach 14 may pass downwardly through the cap and machine the inner surface thereof. In this connection attention is again directed to Figure 3 of the drawings wherein it will be noted that the inner face of the work holder 24 is fashioned with a recess 34 extending downwardly from the base of the recess 32 to the bottom of the work holder and positioned to provide ample clearance for the broach 14.

The work or bearing cap 19 is held in firm contact with the base of the recess 32 during the broaching operation by the arm 22. The arm 22 is shown in Figure 3 of the drawings in its work clamping position wherein the wear-resisting pad 30 securely engages the top of the work 19, and holds the latter against displacement relative to the holder 24 as the broach 14 is moved downwardly to effect the machining operation. The swinging end of the arm 22 is formed with a recess 35 aligned with the recess 24 and of sufficient dimension to provide ample clearance for the passage of the broach 14.

The work holder 25 is formed with a recess 36 in the top face thereof and a pin 37 extends upwardly from the base of the recess 36. As shown in Figure 9 of the drawings, the pin is adapted to engage in the opening provided at the wrist pin end of the connecting rod 20, and the recess 36 is of sufficient dimension to accommodate the connecting rod. It will be understood that the connecting rod 20 is in the form of a forging having the bearing cap 19 integral therewith, and that the bearing cap rests on the base of the recess at the inner end of the holder 25.

Referring now to Figure 10 of the drawings, it will be noted that the base portion of the recess 36 extends beyond the inner end of the holder and is formed with slots 38 at opposite sides of sufficient dimension to provide ample clearance for the passage of the tool 15.

The above arrangement is such that when the holder 25 is in its forwardmost position relative to the tool 15, the slots 38 respectively register with the path of travel of the laterally spaced sets of teeth 40 projecting inwardly from the broach 15. It will be understood that the pin 37 positions the connecting rod forging 20 on the base of the recess 36 to enable the teeth 40 on the broach 15 to sever the cap section 19 from the remaining part of the rod when the holder is located in its operative or forwardmost position.

During the above operation the cap end of the connecting rod forging is firmly held against the base of the recess 36 by the arm 23. In Figure 9 of the drawings the arm 23 is shown in a position wherein the wear resisting pad 30 is in clamping contact with the work, and it will be noted from Figure 10 of the drawings that the width of the pad 30 is less than the lateral spacing between the broach teeth 40, so as not to interfere with movement of the tool 15.

The work holder 24 is secured to the slide 17 for movement as a unit with the latter, and the operation of the slide 17 is so timed with the operation of the slide 12 or broach 14 that when the latter is in its uppermost position, the slide 17 is in its forwardmost position. When in this latter position, the slide positions the work holder 24 with the work 19 in the path of travel of the broach 14, so that the surface of the work is machined as the broach 14 is moved downwardly.

As indicated above the total 15 operates in out-of-phase relationship to the tool 14, so that when the tool 14 is in its uppermost position, the tool 15 is in its lowermost position. The work holder 25 is secured to the slide 18, and the operation of the latter is so timed with respect to the movement of the tool 15 that when the latter is in its inoperative or lowermost position, the slide or tool holder 25 is in its retracted out outermost position. The arrangement is such that the slide 18, together with the work holder 25, is moved inwardly in timed relation to upward movement of the tool 15 to its operative position, so that the work 20 is aligned with the tool 15 when the latter is again moved downwardly. As the tool 15 is returned to its operative or uppermost position, the tool 14 performs its cut on the work 19 and upon completion of this cut, the slide 17 together with the work holder 24 is retracted. Thus it will be noted that one of the tool holders may be unloaded and reloaded during the interval the work in the other tool holder is being processed, and as a consequence, substantially continuous operation results.

It follows from the foregoing that the arms 22 and 23 must be swung to their work clamping positions upon movement of either tool on its operative stroke, and these arms must be moved to their work releasing positions upon completion of the operative stroke of either tool. With this in view, reference is again made to Figure 3 of the drawings, wherein it will be noted that the two arms are simultaneously operated by a member 41 mounted on the bottom surface of the bridge 26 intermediate the arms for sliding movement transversely of the bar 29. Referring to Figure 4 of the drawings, it will be noted that the member 41 is substantially T-shaped in cross sec-

tion, and a pair of gibs 42 are respectively secured to the bottom surface of the bridge 26 at opposite sides of the member 41 and cooperate with the flanges on the latter to guide the same. In any event the bottom surface 43 of the member 42 is tapered and engages the adjacent top surface of the bar 26. The direction of taper is such that movement of the member 41 outwardly applies a cam action on the bar 29 to swing the lower ends or pads 30 on the arms to their respective work clamping positions. On the other hand, movement of the member 41 in an inward direction releases the bar 29 and permits the arms to be swung to their work releasing positions. The extent of movement of the arms between the two above mentioned positions is limited by pins 44 which respectively extend through enlarged openings 45 formed in the arms and have the opposite ends engaging the bridge or support 26.

The member 41 is operated by a rock arm 47 pivotally mounted intermediate its ends on a pin 48 for swinging movement. In the present instance the pin 48 is mounted on the support or bridge 26 with its axis extending parallel to the aligned axes of the pins 28, so that the arm 47 rocks in a plane parallel to the planes of the respective arms 22 and 23. The rock arm 47 is connected to the member 41 at a point between the pin 49 and the lower end of the rock arm by a stud 49. The head of the stud is pivoted to the rock arm 47 by a pin 50, and the shank of the stud extends axially through the member 41. Suitable stop nuts 52 are threaded on the stud beyond the outer end of the member 41, and the latter is urged into engagement with the stop nuts by a coil spring 53. The coil spring 53 surrounds the stud between the inner end of the member 41 and the head of the stud. Actually the coil spring 53 normally urges the tapered or cam face 43 on the member 41 into wedging engagement with the bar 29 and thereby yieldably urges the pads 30 on the work clamping arms into engagement with the work. With this arrangement variations in the dimension of the work may be compensated for without interfering with the clamping action.

Referring again to Figure 3 of the drawings, it will be noted that the rock arm 47 is normally urged in a clockwise direction about the pin 48 to locate the member 41 in its clamping position by a spring pressed plunger assembly 54. The assembly 54 comprises a casing 55 and a plunger 56 slidably mounted in the casing. The inner end portion of the plunger is reduced and extends through the adjacent end of the casing for engagement with the upper end of the rock arm 47. A suitable coil spring 57 is supported in the casing 55 between the outer end of the plunger and adjacent end of the casing for urging the plunger in a direction to swing the rock arm in a clockwise direction about the pin 48.

The rock arm 47 is operated in timed relation to movement of the tool slides 12 and 13 by cams mounted on the slide 21. In the present instance three cams 60, 61 and 62 are suitably secured to the slide 21 for operating the work clamping arms through the rock arm 47. The cam 60 may be considered as the operating cam, and the cams 61 and 62 the releasing cams. The operating cam 60 is in the form of a bar elongated in the direction of movement of the slide 21 and secured to the front face of the slide. The lower end of the cam 60 is formed with a cam face 63 adapted to engage a roller 64 on the lower end of the rock arm to positively swing the rock arm in a

clockwise direction and thereby displace the operating member 41 in an outward direction. As the operating member 41 moves outwardly, the cam face 63 cooperates with the bar 29 to swing the arms 22 and 23 to their work clamping positions. The location of the cam face 63 is such that it engages the roller 64 when one of the work holders is in its operative position and when the other work holder is retracted.

10. The cam 60 is provided with a straight edge 64 extending upwardly from the cam face 63 in parallel relation to the slide 21 to maintain the work clamping arms in their operative position for a predetermined length of time, depending 15 on the length of the edge 64. This length is, of course, sufficient to maintain the work clamping arms in their operative positions throughout the full cutting stroke of the tools.

The releasing cam 61 is secured to the slide 20 above the upper end of the cam 60 in a position to engage the upper end of the rock arm 47 and swing the latter in a counterclockwise direction against the action of the spring 57 to release the member 41 from the bar 29 and thereby release 25 the work clamping arms. The space between the cam 61 and the upper end of the cam 60 is such that the former is not engaged with the rock arm until the roller 65 reaches the upper end of the straight edge 64 on the cam 60. As 30 shown in Figure 5 of the drawings, a pair of rollers 66 are respectively supported at opposite sides of the upper end of the rock arm on a pin 67, and the releasing cam 61 is adapted to engage these rollers.

35. Thus from the foregoing it will be noted that as the cam slide 21 moves downwardly with the tool slide 12, the cam face 63 on the cam 60 engages the roller 65 and swings the rock arm 47 in a clockwise direction to move both the work clamping arms to their operative positions by the member 41. Although both arms 22 and 23 are moved to their work clamping positions, nevertheless, the work holder 24 is the only one in 40 position to cooperate with the arm 22 to clamp 45 a work piece in position for engagement by the tool 14. The other work holder 25 is retracted and does not interfere with movement of the arm 23 to its work clamping position.

The work clamping arms are maintained in 50 their operative positions throughout a downward length of travel of the tool slide 12 corresponding to the length of the edge 64 on the cam 60. As the tool slide 12, together with the cam slide 21, continues downward movement subsequent to the 55 machining operation performed by the tool 14, the releasing cam 61 engages the rollers 66 on the upper end of the rock arm 47 to release the work clamping arms.

When the work clamping arms are released 60 from their operative positions, the work holder 24 is retracted, and the work holder 25 is advanced to a position in operative relation to the tool 15 which has previously been returned to its uppermost position. As the tool 15 is lowered to 65 process the work on the holder 25, the tool slide 12 together with the cam slide 21, is moved upwardly and the work clamping arms are again swung to their operative positions. In this connection reference is again made to Figure 3 of the 70 drawings wherein it will be noted that the upper end of the cam 60 is formed with a cam face 70 similar to the cam face 63 in that it engages the roller 65 on the lower end of the rock arm 67 and swings the latter in a clockwise direction to 75 cause the member 41 to again engage the bar 29

and swing the work clamping arms to their operative position. These arms are retained in their operative position by the straight edge 64 on the cam 60 until the tool 15 completes its cut. When the tool 15 reaches the end of its cutting stroke, the roller 65 is released from the cam 60 and the rollers 66 are engaged by the cam 62 to swing the arm 41 in a counterclockwise direction to release the clamping pressure applied by the member 41 on the arms 22 and 23. In detail the releasing cam 62 comprises complementary sections secured to the slide 21 at opposite sides of the cam 60 in positions to engage both the rollers 66 and thereby swing the rock arm in a direction to again release the work clamping arms from their operative positions. As indicated above the releasing cam 60 is so positioned on the slide that it engages the rollers 66 subsequent to the cutting operation of the tool 15 and as the roller 65 leaves the straight portion 64 of the cam 60.

It follows from the foregoing that the fixture is thoroughly automatic in operation and is especially adaptable to broaching or equivalent machines, wherein a plurality of tools are alternately moved throughout their cutting strokes, and wherein one tool holder is in its operative position while the other is in its retracted position where it may be reloaded while the work in the first tool holder is being processed.

What we claim as our invention is:

1. In a broaching machine including a pair of parallelly arranged alternately operating broach carriers, and a work support for each broach carrier adapted to present the work in operative relation thereto during the working stroke thereof and withdraw it during the return stroke; work clamping means comprising a rockable member provided with a pair of arms for respectively clamping the work on said supports when each is in operative position, and cam means movable with one of said broach carriers for actuating said rockable member on both the working and return strokes thereof, the one operation clamping the work while operated upon by the broach of the said one of said carriers and the other clamping the work when operated upon by the broach of the other carrier.

2. The construction as in claim 1 having a support extending transversely to the direction

of movement of said carriers and spaced in front thereof, to which said support said rockable member is pivoted, a lever also pivoted on said support actuated by said cam means, and a cam carried by said lever engaging said rockable member to depress the same during the working stroke of each broach.

3. The construction as in claim 2 having the rockable member pivoted on the front side of said support and inclining downward towards said broach carriers and having the arms thereof connected by a rod beneath said support, the cam carried by said lever extending between the bottom of said support and said rod to simultaneously depress both arms when the lever is rocked and engage the work alternately thereby in successive operations.

4. The construction as in claim 3 having the lever fulcrumed intermediate its ends, one end of said lever engaging said cam means to operate said rockable member in a downward direction and the other end engaging said cam means to release downward pressure on said rockable member.

5. The construction as in claim 4 in which rollers are mounted on the opposite ends of the lever and said cam means has a portion thereof for engaging a roller actuating the lever to clamp the work, and a portion engaging the opposite roller for releasing clamping pressure on the work.

6. The construction as in claim 5 having a resiliently yieldable element intermediate said lever and the cam carried thereby permitting of clamping work pieces varying in thickness.

LEO I. KAPLAN.
